I. N. LEWIS.
GAS REGULATOR AND TRAP FOR AUTOMATIC GAS OPERATED FIREARMS.
APPLICATION FILED MAY 10, 1916.

1,195,693.

Patented Aug. 22, 1916.

UNITED STATES PATENT OFFICE.

ISAAC NEWTON LEWIS, OF THE UNITED STATES ARMY, ASSIGNOR TO THE AUTOMATIC ARMS COMPANY, OF BUFFALO, NEW YORK, A CORPORATION OF NEW YORK.

GAS REGULATOR AND TRAP FOR AUTOMATIC GAS-OPERATED FIREARMS.

1,195,693.

Specification of Letters Patent. Patented Aug. 22, 1916.

Application filed May 10, 1916. Serial No. 96,514.

To all whom it may concern:

Be it known that I, ISAAC NEWTON LEWIS, colonel of the U. S. Army, a citizen of the United States of America, residing at 5 5 Adelphi Terrace, Strand, London, W. C., England, have invented certain new and useful Improvements in Gas Regulators and Traps for Automatic Gas-Operated Firearms, of which the following is a specification.

10 This invention resides in a structure for attachment to automatically gas-operated firearms whereby the amount of gases of combustion utilized for actuating the gun mechanism may be regulated. Said structure also serves another important function in that it separates solids from gases in transit from the gun barrel to the chamber of the operating piston.

15 20 The invention therefore consists in the structure of parts and in their association and combination substantially as hereinafter set forth and claimed.

25 The drawings which form a part of this specification show only so much of well known automatic gun mechanism as is necessary to a full disclosure of the present invention.

30 35 Figure 1 is a longitudinal vertical medial section through the gun barrel and appurtenances including the gas cylinder and gas chamber. Fig. 2 is a transverse vertical section through Fig. 1 in the plane indicated by line 2-2. Fig. 3 is a side elevation of the gas chamber and Fig. 4 is a plan of the underside thereof. Fig. 5 is a sectional view similar to Fig. 1 with some modifications in the gas regulator and operating means.

40 45 50 The gun barrel is indicated by 5, the gas cylinder by 6, its piston by 7, the gas chamber by 8, and the gas port in the barrel by 9. In Figs. 1 and 2 a radiator casing is represented at 10 surrounding the radiator 11. The gas chamber 8 has a nipple 12 at its upper end registering with the gas port 9. This nipple is preferably screwed into a band 13 surrounding the barrel in the port zone. The outlet port 14 of chamber 8 opens into the gas cylinder 6.

55 The regulator cup of the present invention is indicated by 15. It is closely fitted up into the gas chamber, has its upper end preferably countersunk into the upper wall of said chamber and is screw threaded at

its lower end for engagement with like threads in the lower end of said chamber. This regulator cup has two or more ports through its sides near its upper end in position to register with the outlet port 14. 60 Such ports are indicated by 16 and 17 Fig. 1. The protruding lower end of the cup is provided with means for rotating it to bring the desired port thereof into registry with outlet port 14 or to bring a blank side over 65 said outlet port when it is desired to cut off the flow of gas to the cylinder thereby stopping the automatic action of the gun. One device found effective for this purpose consists of a key 18 which enters a transverse 70 hole in the protruding end of the cup and bears a stud 20 at its other end for insertion in an eyelet or recess 21 in the casing 10. The shank of the key has sufficient spring set to hold the stud in the eyelet till forced 75 out for rotating the cup to change position of ports, or to take the cup out for cleaning. To provide for readily forcing said stud out of its seat a hole 22 is made in the rear end of said key into which the tip of 80 an ordinary service cartridge such as used in the gun here represented may be inserted.

When more than two ports are provided in the wall of cup 15 corresponding holes 85 for the operating key are made in the protruding end of the cup. In Fig. 5 three such ports are shown port 23 having been added to ports 16 and 17. The second transverse hole 24 through the protruding 90 end of the cup provides for the key holding either port 23 in registry with port 14 or a blank opposite 23 over port 14 as desired. The three ports in the cup are graded in size for admission of the required amount 95 of gas to the cylinder 6 as circumstances may demand. The cup 15 simulates the ported plug of an axially discharging rotary valve. Through it however the course of the fluid is the reverse of the usual direction, flowing into the plug first and through its ports to the outlet port.

When the gas regulator described is attached to guns which have not the casing 10, the key may have another form and any 105 suitable stop may be provided therefor. In Fig. 5 said key 18 has its holding stud seated in a ring 25 secured to the underside of the gas cylinder and the rear end of the key is provided with a hook 26 under which 110

the tip of a cartridge may be entered to pry the stud 20 from its seat.

The bottom of the cup 15 is well below the ports in its sides. This is an essential 5 feature of the mechanism since the solid particles due to attrition in firing the gun and to imperfect combustion are driven to the bottom of the cup and are there caught instead of entering the cylinder 6. This 10 helps to keep the cylinder clean and insures a longer period of operation for the piston 7. The additional capacity of the cup provided by the space below the ports also affords an expansion chamber for the gases 15 thereby causing a more prolonged and constant pressure upon the piston 7. The detritus trapped in the cup is readily removed by unscrewing the cup and emptying it. This is quickly done with the key 18 20 which on being pried from its anchorage as above described may be removed from its hole 19 or 24 turned over and again inserted in one of them when its free end will swing clear of other parts due to the spring set 25 therein and the chamfer at its inner end which also assists in the ready application of the key in either position.

The bottom of the cup 15 constitutes 30 really the lower end of the gas chamber 8 and said chamber may be properly characterized as an expansion chamber provided with a pocket below its outlet port for trapping detritus carried by the operating gases. For attaching and detaching the chamber 8 35 from the port band 13 spaces for the prongs of a spanner wrench are provided on its opposite sides between projections 27 and 28.

The invention claimed is—

1. In a gas operated gun the combination 40 of the barrel having a lateral gas port, a gas cylinder, a gas chamber interposed in the path of the gas from the barrel to the cylinder and a cup-shaped ported plug in said chamber with its open end surrounding said 45 port in the barrel for regulating the flow of gas to said cylinder.

2. In a gas operated gun the combination 50 of the barrel having a lateral gas port, a gas cylinder, a gas chamber interposed in the path of the gas from the barrel to the cylinder and having a lateral outlet port at its upper end opening into said cylinder, a cup-

shaped plug seated in said chamber with its open end surrounding said port in the barrel and having ports of different sizes, and 55 means for bringing one or another of said varying ports into registry with said outlet port.

3. In a gas operated gun the combination 60 with the barrel and gas cylinder, of a gas chamber having a pocket below the path of the gas from the barrel to the cylinder for the purpose set forth.

4. In a gas operated gun the combination 65 with the barrel and gas cylinder, of a gas chamber having a pocket below the path of the gas from the barrel to the cylinder, and a rotary ported plug in said chamber for regulating the flow of gas.

5. In a gas operated gun the combination 70 with the barrel and gas cylinder, of a gas chamber having a pocket below the path of the gas from the barrel to the cylinder, a rotary ported plug in said chamber for regulating the flow of gas therethrough, a spring 75 key detachably connected to said plug, and means for anchoring said key in adjusted position.

6. In a gas operated gun the combination 80 with the barrel and gas cylinder, of a gas chamber secured to the barrel at the gas port thereof and having its outlet port into said cylinder near the upper end, a rotary cup inserted in the lower end of said chamber and provided with ports at its upper end 85 registrable with said outlet port and forming a closure for the lower end of said chamber, and a key for rotating said cup.

7. In a gas operated gun the combination 90 with the barrel and gas cylinder, of a gas chamber secured to the barrel at the gas port thereof and having its outlet port into said cylinder near the upper end, a rotary cup inserted in the lower end of said chamber and provided with ports at its upper 95 end registrable with said outlet port and forming a closure for the lower end of said chamber, a detachable spring key for rotating said cup, and a keeper for anchoring said key and cup in fixed position after ro- 100 tation.

In testimony whereof I have affixed my signature.

ISAAC NEWTON LEWIS.
